UNITED STATES PATENT OFFICE

DAVID FRANKLIN YOUNGBLOOD, OF SAN ANTONIO, TEXAS

MASTER OPERATING MECHANISM FOR CELL DOORS AND LOCKS

Application filed August 15, 1929. Serial No. 386,035.

This invention relates to door and lock operating mechanism for a plurality of prison cells and, among other objects, aims to provide important improvements on systems of the general type shown in my Patents, 1,269,244 and 1,611,260. One of the main features is the provision of means whereby either a master door propelling bar or a door locking and unlocking bar may be actuated and controlled by a single manipulating device, such as a lever or hand wheel located in a master control box. Further, the invention contemplates the provision of means associated with the operating mechanism to insure that the selected, operated doors will not be left partly open when the locking bar is moved to locking position. Also, it insures that all selected doors shall be fully unlocked before any of them can be opened.

Other more or less important aims and advantages of the invention will appear in the specification taken in connection with the accompanying drawings, wherein:

Fig. 1 is a fragmentary sectional view showing the preferred form of master operating mechanism;

Fig. 2 is a fragmentary horizontal sectional view showing a top plan of the operating mechanism;

Fig. 3 is a fragmentary sectional view taken on the line 3-3 of Fig. 1; and

Fig. 4 is a sectional view taken on the line 4-4 of Fig. 3.

In the master locking and door operating systems for jails or prisons wherein a series of cell doors are controlled and selectively operated from a central station, the mechanism heretofore employed has included separate levers or hand wheels connected to the master locking bar and the master propelling bar. Also, the operating devices for the bars are independent of each other. Examples of such operating and controlling mechanism are disclosed in my aforesaid patents. The present invention provides selectively operable means whereby a single lever or hand wheel may be employed to actuate either of the bars and associated means to lock the other bar and hold it immovable

until the selected bar has been fully actuated. Further, the selected embodiment of the improved mechanism is so constructed and arranged as to enable a jailer to complete the operations very quickly and expeditiously; while an unauthorized person or a prisoner cannot open any doors without knowing the proper combination.

In the drawings, the preferred form of the mechanism is shown as being adapted to control and operate the locks and doors of a series of cells which are usually arranged in a row. The arrangement of the cell doors and locks, the operating connections between them and the master bars, and the selecting mechanism for the locks constitute no part of the subject matter of this application. Hence, any illustration of such mechanism is unnecessary. It is sufficient here to state that a master lock operating bar 10 and a parallel master door propelling bar 11 are arranged in an overhead casing or longitudinal housing 12 and are adapted to be connected to selected locks and doors of a series or row of cells.

In the present instance, a single master operating handle in the form of a hand wheel 13 is arranged in a master inset control box 14 like that disclosed in my copending application, Ser. No. 373,532, filed June 25, 1929 and is adapted to be selectively connected to actuate either of said bars by means of transmission gearing and gear shifting mechanism under the control of the jailer.

Referring to Figs. 1, 2 and 3, the hand wheel 13 is there shown as being mounted on a shaft 15 which is journaled in bearings 16 and 17 within the control box behind a vertical panel 18. Herein, a bevel gear 19 on the shaft 15 meshes with a similar gear 20 on a vertical shaft 21 journaled at its upper and lower ends in suitable brackets 22 in the form of gear casings. Another bevel gear 23 in the upper casing 22 meshes with a gear 24 on a horizontal shaft 25 arranged to operate the transmission mechanism about to be described.

Referring to Figs. 3 and 4, the shaft 25 has a bevel gear 26 meshing with a combined bevel and spur gear 27 rotatably mounted on

a fixed shaft 28 in a frame 29 within the housing 12 as best shown in Fig. 3. A pair of spur gears or pinions 30 and 31 conveniently cast are shown as being slidably and rotatably mounted on a transverse shaft 32 and are adapted to engage racks 33 and 34, respectively, on the bars 10 and 11. Herein the bars have rearward rack extensions through the frame 29 and the racks are so spaced that they straddle the two gears 30 and 31 when the gears are in neutral position as shown in Fig. 4, the upper edges of the bars being guided by rollers 35. It will now be seen that the gears or pinions are arranged to be shifted so that one of them engages the rack on one of the bars.

To shift the gears so that they will engage the respective racks, there is shown a shifting yoke 36 pivotally mounted on a vertical pivot pin 37 and engaging an annular groove 38 on the gear casting. This yoke is connected to be shifted by means of a hand lever 39 extending through an opening in the panel 18 and preferably having three notches 40 to engage the panel and hold the lever in either shifted position or in the neutral position, the middle notch holding the lever in its neutral position. As shown in Fig. 1, the lever is pivotally connected to a vertical pivoted rocker arm 41 which, in turn, is pivoted to a link 42 also pivotally connected to an operating arm or bell crank arm 43 on the yoke 36 (Fig. 2). The arrangement is such that the gears 30 and 31 may be quickly shifted into mesh with the respective racks 33 and 34 by lifting and pushing or pulling the manipulating lever 39 and then turning the hand wheel 13. The spur gear 30 always remains in mesh with the gear 27, the teeth being sufficiently wide for this purpose. In Fig. 3, both bars have been actuated to unlock and open the selected doors.

It is desirable to lock both of the master bars 10 and 11 when the gears are in their neutral position and always to lock one bar while the other bar is being actuated and thereby positively prevent any unauthorized manipulation of the doors or the locks. Assume, for example, that several selected doors have been unlocked by actuating the bar 10, it is important that the prisoners in the selected cells shall not push the doors open until the jailer is ready to release them, or possibly until attendants are stationed at the respective doors to receive the prisoners. Moreover, it is highly desirable that the jailer shall be assured that all selected locks are fully released or unlocked when he shifts the gears to open the doors and that all doors shall be fully closed when he shifts the gears to lock them. To these ends, a shiftable locking bolt 44 is shown as being arranged to co-operate with and engage both master bars and is preferably, though not necessarily,

connected to be actuated by the gear shifting yoke 36.

In the illustrative example, the locking bolt 44 is in the form of a horizontal bar which is slightly longer than the space between the rack extensions 33 and 34, and it is slidably mounted in alined openings in two spaced, vertical brackets 45 on the transmission frame casing 29 (Figs. 2 and 3). As shown, the yoke 36 has a forwardly extending arm 46 beyond the pivot pin 37 and this arm has a forked or bifurcated end engaging opposite flat portions 47 conveniently provided at the center of the bolt. The idea is to shift the bolt in one direction when the gears are shifted in the opposite direction. Herein, the master locking bar 10 has a recess 48 to receive the bolt when this bar is pulled back to its locking position and a hole 49 is drilled through the rack to receive the bolt when the bar is pushed to its unlocking position. Also, the propelling bar presents a through-opening 50 to receive the bolt when this bar is in its door-closing position and an opening 51 alines with the bolt when the bar is in its door-opening position, as shown.

When all of the cell doors are closed and locked, the locking bar 10 and the propelling bar 11 will be pulled back so that the recess 48 and the hole 50 will be alined with the bolt 44. If the transmission gears are in their neutral position, the bolt will engage both the recess and the opening, thus locking both master bars. These are the positions in which the parts are usually left by the jailer. It will now be understood that the first operation that is necessary is to select the locks to be actuated or unlocked. As previously stated, the particular selector mechanism does not constitute a part of this application. It may be either electrical or mechanical or a combination of electrically and mechanically controlled devices. In the present instance, it is sufficient to state that the locks may conveniently be selected by means of small individual, notched hand levers 52 projecting through the panel 18 and easily accessible to the operator or jailer. One such lever is usually provided for each door lock and is suitably connected to the selecting mechanism at the door by means of links and levers which it is not necessary to describe. However, reference is again made to the mechanism shown and described in my Patent Nos. 1,269,244 and 1,611,260 as being suitable for this purpose.

After the locks have been selected by actuating the small levers 52 or suitable electric switches, as the case may be, it is necessary to push the master locking bar 10 forwardly or to the left as shown in Figs. 2 and 3. For this purpose, the gear shifting lever 39 is lifted and pulled out until the rear notch 40 engages the panel, thus shifting the gear 30

into mesh with the rack 33. After the gear is shifted, the yoke will slide the bolt 44 out of the recess 48 and its opposite end will project through the opening 50. This leaves the locking bar free to move. Then, the jailer turns the hand wheel until it stops and the locking bar has moved to the left as far as it can go. This movement or operation brings the hole 49 into alignment with the bolt 44.

10 While this operation is in progress, the bolt extending through the hole 50 locks the propelling bar and prevents any unauthorized movement thereof or of the doors operatively connected thereto.

15 The jailer next shifts the gear 31 into mesh with the rack 34 on the propelling bar and simultaneously shifts the bolt 44 out of the hole 50 into and through the hole 49 in the rack of the locking bar. He then turns the hand wheel in the proper direction and pushes the propelling bar as far forwardly or to the left as it will go, so that the doors operatively connected thereto are fully opened. This brings the recess 51 into alignment with the 20 bolt 44. While the propelling bar was being moved or operated, it will be seen that the locking bar was held locked by the bolt 44.

25 After the selected doors have been unlocked and fully opened, it is sometimes desirable to 30 guard against any of the prisoners closing the doors and possibly locking up one of the jailers who might be mingling with them. To prevent this, the bolt 44 is shifted to the position shown in Fig. 3 by the simple expedient 35 of raising the lever 39 and pushing it inwardly until the middle notch engages the panel 18 as shown in Fig. 1.

40 To close and again lock the doors, the gear 31 is engaged with the rack on the propelling bar, thereby disengaging the bolt from the recess 51 and the hand wheel is again rotated to pull the bar back as far as it will go or until the hole 50 is brought into alignment with the bolt. The gear 30 is 45 next shifted to engage the rack on the locking bar thereby shifting the bolt 44 into and through the hole 50. The hand wheel is again rotated to move the bar to its locking position, and then the bolt 44 is 50 again shifted to engage both bars and the gears are shifted to neutral position. It might be added here that the jailer cannot shift the gear 31 or the bolt 44 until the hole 50 does align with the bolt. This insures 55 that all of the doors are fully closed before the locking bar can be operated. Likewise, the gear 31 cannot be shifted into mesh with the rack on the propelling bar until the locking bar has been moved to the unlocking position and the hole 49 is aligned with the 60 bolt 44.

65 Adverting to the recesses 48 and 51 in the racks 33 and 34, the reason that they are not drilled through the racks is that there is never any occasion to shift the bolt through

any such holes. As above described, the bolt is first shifted out of the recess 48 to release the locking bar. When the bolt is in the position shown in Fig. 3, it has to be shifted out of the recess 51 to release the propelling bar. The bottoms of these recesses therefore prevent the bolt from being shifted in the wrong direction even if the jailer should temporarily forget his combination.

70 After the cycle of operations has been completed, the jailer shifts the lever 39 to its neutral position and all of the selecting levers 52 to their inactive position and leaves the bolt 44 in engagement with the recess 48 and hole 50 in the bars 10 and 11. This prevents any unauthorized movement of the master bars even if some of the prisoners should gain access to them from their cells. The door of the control box is then closed and locked as described in my aforesaid copending application. It is thus not only practically impossible for any unauthorized person to gain access to the master operating mechanism within the control box, but also exceedingly difficult for anyone to manipulate the mechanism without knowing the proper combination. The described cycle of operations, as is already apparent, requires familiarity with the mode of working the shifting levers and the hand wheel. The 80 whole thing is in the nature of a combination which is quite as difficult to work as that in a combination lock.

85 From all of the foregoing description, it will be seen that the single hand wheel performs all of the operations heretofore performed by a pair of levers or hand wheels and that the relatively simple and inexpensive transmission mechanism makes it possible to so coordinate the movements and operations of the master locking bar and propelling bar as to avoid almost any possibility of a serious mistake. Moreover, the method of operating the mechanism is so utterly different from the ordinary mechanism that it is exceedingly difficult for an inexperienced person or visitor to manipulate it and assist in the escape of prisoners.

90 It is desired again to emphasize some of the main advantages of the particular transmission and bar-locking mechanism herein shown and described. As has already been stated, both the master propelling bar and lock operating bar are locked when the transmission gears are in neutral position. The 95 pinion for operating the master propelling bar cannot be shifted until all of the cell doors have been fully unlocked. The master propelling bar is held locked while the lock operating bar is being actuated. The lock 100 operating bar is locked while the master propelling bar is being operated. Also, the arrangement prevents the shifting of the gears 105 out of engagement with the master propelling bar until the selected cell doors are entirely 110 locked.

closed, thus insuring that none of the doors will be left partly open. Further, the gear for operating the locking bar cannot be shifted out of engagement with the rack on the locking bar until all of the selected doors are either entirely locked or unlocked. The importance of many of these features can only be appreciated by a jailer of long experience, who knows the habits of ingenious criminals and the dangers incident to maintaining proper order among them and keeping them securely incarcerated. Hence, further elaboration herein is believed to be unnecessary.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a master operating system for cell doors and locks having locking mechanism and door propelling mechanism, a single actuating element; and means to connect said element so that it will actuate either the locking mechanism or the door propelling mechanism.
2. In a master operating system for cell doors and locks having locking mechanism and door propelling mechanism, a single actuating element; and means selectively to connect said element to actuate either the locking mechanism or the door propelling mechanism.
3. In a master operating system for cell doors and locks having a master lock operating member and a master door propelling member, a single actuating element for both members; and means connecting said element to actuate said members.
4. In a master operating system for cell doors and locks having locking mechanism and door propelling mechanism; a single actuating element; and transmission gearing arranged selectively to connect said element to actuate the locking mechanism or the door propelling mechanism.
5. In a master operating system for cell doors and locks having a master lock operating member and a master door propelling member, a single actuating element for both members, and transmission mechanism selectively to connect said element to actuate said members.
6. In a master operating system for cell doors and locks having a master lock operating bar and a master door propelling bar, a single manual actuating means; and means selectively to connect said actuating device to actuate said bars.
7. In a master operating system for cell doors and locks having a master lock operating bar and a master door propelling bar,

to actuate said bars including transmission mechanism to connect said actuating means to actuate either of said bars.

8. In a master operating system for cell doors and locks having locking mechanism and door propelling mechanism, a single actuating element; means to connect the actuating element to actuate either the locking mechanism or to the door propelling mechanism; and associated means lock the inactive mechanism while the other mechanism is being actuated.

9. In a master operating system for cell doors and locks having a master lock operating bar and a master door propelling bar, a single actuating element for both members; means to connect the actuating element to actuate either of said bars; and means associated with the connecting means to lock one of the bars and hold it locked when the other bar is connected.

10. In a master operating system for cell doors and locks having a master lock operating member and a master door propelling member, a single actuating element for both members; means to connect said element to actuate either of said bars; and a locking bolt associated with said connecting means to engage and hold either of said members locked when the other member is being actuated.

11. In a master operating system for cell doors and locks having a master lock operating bar and a master door operating bar, a single manual actuating means; transmission gearing arranged to connect the actuating means to actuate either of said bars; and an associated locking bolt to engage the inactive bar while the other bar is being actuated.

12. In a master operating system for cell doors and locks having a master lock operating bar and a master door propelling bar, a single manual means connected selectively to actuate said bars including transmission mechanism to engage said means so as to actuate either of said bars.

13. In a master operating system for cell doors and locks having a master lock operating bar and a master door propelling bar, manual means connected selectively to actuate said bars including transmission mechanism to effect engagement of said means with either of said bars; and means to manipulate the transmission mechanism to effect such selective engagement.

14. In a master operating system for cell doors and locks having a master lock operating bar and a master door propelling bar, manual means connected selectively to actuate said bars including transmission gears shiftable to engage said bars; and gear shifting means to effect the selective engagement.

15. In a master operating system for cell doors and locks having a master lock oper-

ating bar and a master door propelling bar, manual means connected selectively to actuate said bars including transmission gears shiftable to engage said bars; and a manual gear shifting lever for said transmission gearing.

16. In a master operating system for cell doors and locks having a master lock operating member and a master door propelling member, a single actuating element for both members; transmission gearing to connect said element to actuate said members; a gear shifting lever to effect selective engagement of said gearing with said members; and locking means also connected to be actuated by said lever to lock and hold the inactive member when the gearing is connected to actuate the other member.

17. In a master operating system for cell doors and locks having a master lock operating member and a master door propelling member, a single actuating element for both members; transmission gearing connecting said element to actuate said members; a gear shifting lever to effect selective engagement of said gearing with said members; shiftable locking means connected to said lever and arranged to be shifted into engagement with the inactive member when said gearing is connected to the other member.

18. In a master operating system for cell doors and locks having a master lock operating member and a master door propelling member, a single actuating element for both members; transmission gearing connecting said element to said members; a gear shifting lever connected to effect selective engagement of said gearing with said members; a shiftable locking bolt arranged to engage either or both of said members; and pivoted shifting arms connecting said lever to said gearing and said locking bolt to shift them so that the locking bolt engages the inactive member when the gear shift is made to actuate the other member.

19. In a master operating system for cell doors and locks having a master lock operating member and a master door propelling member, a single actuating element for both members; transmission gearing connecting said element to said members; a gear shifting lever to effect selective engagement of said gearing with said members; a shiftable locking bolt arranged to engage either or both of said members; a shifting yoke connecting the lever to the gearing; and a shifting arm for the locking bolt integral with said yoke arranged to shift the locking bolt into engagement with one of the members when the gear shift is made to actuate the other member, said locking bolt also being so constructed and arranged as to engage both members when the gearing is in neutral position.

20. In a master operating system for cell doors and locks, a master locking bar and a

master door propelling bar each having a rack at one end; and a single manual actuating means selectively engageable with said racks to actuate either bar.

21. In a master operating system for cell doors and locks, a master locking bar and a master door propelling bar each having a rack at one end; and a single manual actuating means for said bars including transmission gears selectively shiftable into engagement with said racks to actuate either bar.

22. In a master operating system for cell doors and locks, a master locking bar and a master door propelling bar each having a rack at one end; a rotatable shaft adjacent to the racks on said bars; gears slidably and rotatably mounted on said shaft and adapted to be shifted into engagement with the racks; a single actuating means to rotate the shaft; and gear shifting means having a shifting element adjacent to said actuating means.

23. In a master operating system for cell doors and locks, a master locking bar and a master door propelling bar each having a rack at one end; a transmission device including shiftable gears arranged to engage and actuate either of the racks; a hand wheel connected to rotate said gears; and gear shifting means including a shifting lever adjacent to the hand wheel whereby the hand wheel is connected to actuate either bar.

24. In a master operating system for cell doors and locks, a master locking bar and a master door propelling bar each having a rack at one end; a transmission device including shiftable gears arranged to engage the racks; a hand wheel connected to rotate said gears; manual gear shifting means including a pivoted yoke engaging the gears; a locking bolt arranged between said bars and selectively shiftable into engagement therewith; and a bolt shifting arm integral with said yoke and on the opposite side of the pivot so that as a gear is shifted into engagement with the rack of one bar, the bolt will be shifted in the opposite direction to release that bar and engage and lock the other bar.

25. In a master operating system for cell doors and locks wherein a master locking bar and a master propelling bar are arranged parallel with each other; racks on one end of each of the bars; a transmission casing extending across and below the bars; a transverse shaft in said casing adjacent to said racks; a pair of pinions slidably mounted on said shaft and engageable with the respective racks; a gear shifting yoke mounted on a vertical pivot in said casing; a remote hand lever connected to said shifting yoke; and a single hand wheel connected to actuate said pinion shaft.

26. In a master operating system for cell doors and locks wherein a master locking

bar and a master propelling bar are arranged parallel with each other; racks on one end of each of the bars; a transmission casing extending across and below the bars; a transverse shaft in said casing; a pair of pinions slidably mounted on said shaft and engageable with the respective racks; spaced brackets on said casing between said racks; a shiftable locking bolt slidably mounted in openings in said brackets and extending across the space between the bars; said bars having spaced apertures to register with and to receive said locking bolt only when they are moved to either end of their travel; a single pivoted shifting element engaging said gears and said locking bolt; a shifting lever operatively connected to said shifting element to shift a pinion into mesh with the rack on one bar and the locking bolt out of engagement with that bar and into an aperture in the other bar; and a single manual actuating element connected to said pinion shaft to move the bars in either direction.

27. In a master operating system for cell doors and locks wherein a master locking bar and a master propelling bar are arranged parallel with each other; racks on one end of each of the bars; a transmission casing extending across and below the bars; a transverse shaft in said casing; a pair of pinions slidably mounted on said shaft and engageable with the respective racks; spaced brackets on said casing between said racks; a shiftable locking bolt slidably mounted in openings in said brackets and extending across the space between the bars; said bars having spaced apertures to register with and to receive said locking bolt only when they are moved to either end of their travel; a single pivoted shifting element engaging said gears and said locking bolt; a lever connected to said shifting element to shift a pinion into mesh with the rack on one bar and the locking bolt out of engagement with that bar and into an aperture in the other bar; and master actuating means to rotate the pinions including a shaft having a hand wheel; and geared connections between the hand wheel and the transmission gears.

28. In a master operating system for cell doors and locks wherein a master locking bar and a master propelling bar are arranged parallel with each other; racks on one end of each of the bars; a transmission casing extending across and below the bars; a transverse shaft in said casing below said racks; a pair of pinions slidably mounted on said shaft and engageable with the respective racks; spaced brackets on said casing between said racks; a shiftable locking bolt slidably mounted in openings in said brackets and extending across the space between the bars; said bars having spaced apertures to register with and to receive said locking bolt only when they are moved to either end of their

travel; a single pivoted shifting element engaging said gears and said locking bolt; a master control box having a panel; a shifting lever connected to actuate said shifting element and projecting through said panel; an actuating shaft also projecting through said panel and having a hand wheel thereon; a vertical shaft geared to said hand wheel; and geared connections between said vertical shaft and said pinions.

29. In a master operating system for cell doors and locks wherein a master locking bar and a master propelling bar are arranged parallel with each other; racks on one end of each of the bars; a transmission casing extending across and below the bars; a transverse shaft in said casing; a pair of pinions slidably mounted on said shaft and engageable with the respective racks; spaced brackets on said casing between said racks; a shiftable locking bolt slidably mounted in openings in said brackets and extending across the space between the bars; said bars having spaced apertures to register with and to receive said locking bolt only when they are moved to either end of their travel; a single pivoted shifting element engaging said gears and said locking bolt; a master control box having a panel; a shifting lever connected to actuate said shifting element and projecting through said panel; an actuating shaft also projecting through said panel and having a hand wheel thereon; and geared connections between said vertical shaft and said pinions.

30. In an operating system for cell doors and locks, parallel master bars adapted to be connected to the locks and the doors and arranged to be moved longitudinally to actuate the same; a shiftable locking bolt arranged transversely between the bars and adapted to engage either one or both of the bars; the lock actuating bar presenting a recess alining with the bolt when the bar is in locking position and presenting an opening therethrough to aline with and receive the bolt when the bar is shifted to unlocking position; the door propelling bar presenting an opening alining with the bolt when the bar is in door closing position and presenting a recess therein also to aline with the bolt when the bar is moved fully to open the doors; and means to shift the locking bolt and release one bar at a time to be actuated while it holds the other bar locked, the arrangement being such that the master door propelling bar cannot be released until the locking bar has been moved fully to unlock all of the connected door locks and that the locking bar cannot be released until the propelling bar has fully closed the doors.

31. In a master operating system for cell doors and locks having a master door propelling bar and a master lock operating bar and means to actuate said bars, shiftable bar

locking means arranged to engage one or both of said bars when they are either in door closing and door locking positions or in door opening and door unlocking positions and adapted to be released from only one bar at any time so that the released bar may be actuated; and means to shift said bar locking means.

5 In testimony, that I claim the foregoing as my own, I have hereto affixed my signature.

CERTIFICATE OF CORRECTION.

Patent No. 1,785,470.

Granted December 16, 1930, to

DAVID FRANKLIN YOUNGBLOOD.

It is hereby certified that error appears in the printed specification of the above numbered patent requiring correction as follows: Page 4, line 60, claim 6, for the word "means" read device; same page, line 66, claim 7, strike out the words "to actuate said bars including" and insert instead manual actuating means; and; same page, line 74, claim 8, strike out the word "to" and insert the same before "lock" in line 75; page 6, line 18, claim 26, before the word "to" insert the words so as; and that the said Letters Patent should be read with these corrections therein that the same may conform to the record of the case in the Patent Office.

Signed and sealed this 13th day of January, A. D. 1931.

**M. J. Moore,
Acting Commissioner of Patents.**
